A. C. Barstow, of Providence R. I.
Letters Patent No. 986. Dated Jan. 19th 1858.

The Schedule referred to in these Letters Patent and making part of the same.

To all persons to whom these presents shall come.

Be it known that I, A. C. Barstow of Providence in the County of Providence and State of Rhode-Island, have produced a new and original design for a parlor Cooking Stove and I do hereby declare that the said new design is fully described and represented in the following Specification and accompanying drawings to which reference is herein after made.

The figures of the accompanying plates of drawings represent my new design. In plate 1. fig. 1 is an elevation of the front plate. In Plate 2. fig. 2. is an elevation of the side plate, and fig. 3. is a cross section of the same taken in the plane of the line A.B. In plate 3. fig. 4. is a plan or top view of the bottom plate.

The front plate fig. 1. has across its top the ornamental leaf work a.a. &c, on the sides the vines, b.b. &c and across the figures c.c. &c. The corners over the fire chamber are ornamented with figures composed of vines and scrolls, d.d. &c.

The side plate fig. 2. has across its top the leaves a.a. and on the sides the vines, b.b. The oven-door e.e. is ornamented with raised figures f.f. and in its center with a figure g.g. composed of leaves and scrolls. The panel h.h. is ornamented in a similar manner to the oven-door, e.e.

Des. 980

The bottom plate fig. 4 plate 3, has on it the moldings, i. i. &c. and the leaf work, a. a. extending entirely around it.

Having thus described my new design, I shall state my claim as follows.

What I claim as my invention or production and desire to have secured to me by Letters Patent is the new design for a parlor cooking stove consisting of the vine and leaf work &c. herein above described and represented in the drawings
